UNITED STATES PATENT OFFICE.

WILLIAM S. HAMM, OF HUBBARD WOODS, AND HARRY A. DOUGLAS, OF CHICAGO, ILLINOIS, ASSIGNORS TO THE ADAMS & WESTLAKE COMPANY, OF CHICAGO, ILLINOIS, A CORPORATION OF ILLINOIS.

DESIGN FOR AN AUTOMOBILE-LAMP.

44,306.

Specification for Design.

Patented July 8, 1913.

Application filed February 14, 1912. Serial No. 677,634. Term of patent 14 years.

To all whom it may concern:

Be it known that we, WILLIAM S. HAMM and HARRY A. DOUGLAS, citizens of the United States, residing at Hubbard Woods and Chicago, respectively, in the county of Cook and State of Illinois, have invented a new, original, and ornamental Design for Automobile-Lamps, of which the following is a specification, reference being had to the accompanying drawing, forming a part

thereof and showing a side elevation of the lamp,

We claim—

The ornamental design for an automobile lamp, as shown.

WILLIAM S. HAMM,
HARRY A. DOUGLAS,

Witnesses:

LOUIS K. GILLSON,
E. M. KLATCHER.
